UNITED STATES PATENT OFFICE.

HENRY F. POPE, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,072,163.

Specification of Letters Patent.

Patented Sept. 2, 1913.

Application filed August 1, 1908. Serial No. 446,439.

To all whom it may concern:

Be it known that I, HENRY F. POPE, a citizen of the United States, and a resident of Cleveland, in the county of Cuyahoga and State of Ohio, have invented a new and useful Car-Coupler, of which the following is a full, clear, and exact description, reference being had to the accompanying drawings, forming part of this specification, in which—

Figure 1 is a plan view of two car couplers coupled together and constructed in accordance with my invention; Fig. 2 is a front elevation of one of the couplers, 15 and Fig. 3 is a side elevation thereof partly in section; and Fig. 4 is a plan view partly in section showing another form of the invention.

The greatly increasing stresses which are 20 put upon car couplers by the increase in the length and weight of the trains and locomotives have caused injury to the couplers which, as heretofore constructed, have sometimes proved inadequate to withstand 25 the heavy strains of buffing. The coupler which I have invented and which is described herein overcomes these difficulties by reason of its great strength and ability to resist buffing strains.

As shown in the drawings, 2 represents 30 the head of the coupler, and 3 is the knuckle. The coupler is formed at its sides with outwardly projecting flanges or wings 4 and 4^a having flat buffing faces 4' and 4^a'. These 35 flanges extend outwardly from the opposite sides of the coupler and are adapted to match and abut against corresponding flanges on an opposing coupler. The flanges are backed up by ribs 7 and 7^a which extend rearwardly along the places where the coupler 40 head joins the shank 8 and merge into the shank so as to provide a strong backing for the lugs.

Another part of my invention which I 45 deem preferable resides in combining with the above features a peculiar contour of the buffing face of the coupler and the buffing face of the knuckle. As shown in Fig. 1, the buffing face 9 of the coupler and the 50 buffing face 10 of the knuckle are made par-

allel and at right angles to the longitudinal axis of the coupler shank, so that when two couplers of this kind are coupled together the face of the knuckle will have a broad buffing bearing against the coupler, and this 55 combined with the buffing bearings presented by the faces 4' reduces to a minimum the liability of fracture due to the strains to which the coupler is subjected. In order to give a thoroughly efficient 60 buffing surface, the upper and lower lines A—A and B—B of the contour face of the coupler at the places against which the knuckle of the opposing coupler has a bearing are made horizontal, as shown in Fig. 65 2, instead of being curved downwardly at the top and upwardly at the bottom toward the guard arm and lugs, as heretofore. Previous constructions in this regard have 70 the consequence that when the couplers are standing at different heights and the knuckle of one coupler opposes the top of the face of the opposing coupler, the buffing surfaces thereon are reduced materially.

The shank of the coupler is provided at 75 its sides with vertical shoulders 11, and with transverse horizontal bolt holes 12. When the coupler is attached to the frame of a radial draft gear, the side plates of the frame are abutted against the shoulders 11 80 and are fixed to the shank by bolts extending through the holes 12. The base of the shank also has holes 13 for receiving lugs on a wearing plate.

Other modifications may be made by those 85 skilled in the art. The coupler is especially designed for use with a radial draft gear.

I claim as my invention:

1. A car coupler for radial draft gears 90 having vertically-extending shoulders at its sides, said shoulders being located to the rear of the coupler-head, laterally-projecting buffing flanges at each side of the head, and webs projecting laterally from said head 95 and extending from said buffing flanges to the vertically-extending shoulders.

2. A car coupler for radial draft gear 100 having a head, a shank and integral buffing flanges projecting laterally from the head

and webs projecting rearwardly from and integral with said flanges and laterally from and integral with the head and shank at every point throughout their length and terminating in vertically disposed shoulders on the shank, the said shoulders being adapted to abut against a supporting frame.

In testimony whereof, I have hereunto set my hand.

HENRY F. POPE.
